AUTOMATIC SEPARATOR CUTOUT SWITCH

Marion E. Frost, Catonsville, Md.

Application October 5, 1951, Serial No. 249,933

9 Claims. (Cl. 340—222)

1

The present invention relates to improvements in an automatic separator cut-out switch and has for an object the provision of an improved device of this kind which will automatically shut off the separator in case of machine failure and at the same time close an alarm circuit to actuate an alarm to warn the attendant of such failure.

Another object of the present invention is to provide an improved structure in which the means for shutting off the separator and closing the alarm circuit is actuated by the oil which is being purified by the separator.

A further object of the present invention is to provide an improved switch of this character, the various parts of which may be mounted upon a base to provide a unitary structure so that the device is capable of being set up quickly and easily at any desired location.

A still further object of the present invention is to provide an improved device of this kind which is capable of being adjusted so that the time of actuation of the device may be varied.

The present invention aims to provide an improved switch of this type which comprises relatively few parts, is economical to manufacture and easy to maintain in proper operating condition.

With the foregoing and other objects in view, the invention will be hereinafter more fully described and more particularly pointed out in the appended claims.

In the drawings, in which the same parts are denoted by the same reference numerals throughout the several views,

Figure 1 is a perspective view of the improved device constructed in accordance with the present invention,

Figure 2 is a sectional view taken on the line 2—2 of Figure 1,

Figure 3 is a sectional view taken on the line 3—3 of Figure 2, and

Figure 4 is a fragmentary side elevational view of the improved device with parts in section and showing diagrammatically the separator and alarm electric circuits.

Referring more particularly to the drawings, 10 indicates a base of insulating material which may be made of micarta or other suitable material. The base 10 may be made of any desired size and shape but in the present illustration is shown to be rectangular. A lever support 11 which may be made of sheet brass or other appropriate material in the form of a substantially flat rectangularly shaped plate is secured to the upper face of the rear end portion of the base 10 by fasten-

ing elements, such as the screws 12 and nuts 13. An arm 14 extends upwardly from each side of the support 11 adjacent the forward edge and each arm has its upper free end portion apertured to receive a pivot element 15 which may be in the form of a rivet. The pivot element 15 also extends through each of apertured ears 16 which extend downwardly from the opposite sides of a cup actuated lever 17 so that the lever 17 is pivotally mounted on the support 11. The main body portion of the lever 17 is substantially diamond shaped and the sides of the main body portion between the points of the diamond are concave.

15 The side points of the diamond have the ears 16 bent downwardly therefrom and the rear point 18 is apertured to receive therethrough the screw threaded upper end of an adjusting member or pin 19. An adjusting or tensioning nut 20 is received by the portion of the pin 19 which extends above the rear point 18 and a lock nut 21 is received by the portion of the pin 19 just below the rear point 18. The lower end portion of the adjusting member 19 has an eye 22 for receiving 20 the upper end portion of a coiled tension spring 23. The lower end of the spring 23 is received by an opening 24 formed in a lug 25 which extends upwardly from the intermediate portion of the rear edge of the support 11.

25 The forward point of the diamond shaped portion of the lever 17 extends forwardly to provide an elongated arm 26 the free end portion of which terminates at a point forwardly of the forward edge of the base 10. A wire or rod 27 which may be made of brass or other suitable material and may be of any desired thickness, for example, one-eighth of an inch in diameter, is secured to the upper face of the lever 17 in any suitable manner. The wire 27 is coextensive with the arm 26 of the lever 17, extends forwardly thereof a short distance as indicated at 28 and then extends downwardly to a point substantially flush with the lower face of the base 10. The portion 28 of the wire 27 then extends forwardly as indicated at 29 and projects downwardly below the base 10 to form an attaching portion 30 which is secured in any appropriate manner to the inner face of the upper portion of a cup 31. A boss 32 having an orifice 33 extending therethrough extends downwardly from substantially the medial portion of the bottom of the cup.

35 At 34 is indicated the discharge line or overflow pipe from the centrifuge of an oil separator or purifier through which line water is intermittently discharged. The outlet end of the pipe

34 is positioned above the cup 31 so that the fluid flowing from the pipe 34 will enter the cup 31.

The spring 23 is set under sufficient tension to counterbalance the cup so that the cup and the arm 26 of the lever 17 are held in their raised position, that is the inoperative position of the lever. In order to check the upward movement of the arm 26 a lever stop generally indicated at 35 is provided.

The lever stop 35 is of substantially inverted U-shape and comprises a pair of legs 36 connected at their upper ends by a connecting piece 37 and having on their lower ends apertured out-turned feet 38 which are secured to the upper face of the base 18 by screws 39 and 40. The lever stop 35 is secured to the base 18 adjacent the forward edge thereof and the legs 36 are disposed on opposite sides of the lever arm 26 to serve as guides for the arm 26 in its movements. The connecting piece 37 overlies the arm 26 and is disposed in the path of its upward movement so as to limit the upward movement of the arm 26.

An electric switch generally indicated at 41 is mounted on the upper face of the base 18 rearwardly of the lever stop 35. The switch 41 may be secured to the base 18 by bolts 42 which extend downwardly through the housing 43 of the switch and have their lower screw threaded ends received by suitable openings in the base. The lower ends of the bolts 42 receive nuts 44 for holding them in position. A contact member 45 is fixed to a portion 46 of the switch which may be made of insulating material and an operating rod 47 is slidably received by aligned openings in the contact member 45 and portion 46.

A movable contact member 48 is fixed to the lower end portion of the rod 47 and a push button 49 is carried by the upper end of the rod 47 in the path of downward movement of the arm 26. The movable contact 48 is normally held in its raised position in engagement with the fixed contact 45 by a coiled spring 50 which encircles the intermediate portion of the rod 47 and has its opposite ends engaging the portion 46 and the push button 49. The fixed contact 45 is connected to one end of a wire 51 which may form a part of an electric motor circuit for a motor 52. The movable contact 48 is connected to one end of a wire 53 which may also form a part of the motor circuit.

A second electric switch generally indicated at 54 is also mounted on the upper face of the base 18 rearwardly of the switch 41. The switch 54 may be secured to the base 18 by bolts 55 which extend downwardly through the housing 56 of the switch and have their lower screw threaded ends received by suitable openings in the base. The lower ends of the bolts 55 receive nuts 57 for retaining them in proper position. A contact member 58 is fixed to a portion 59 of the second switch which may be of insulating material and an operating rod 60 is slidably received by aligned openings in the contact member 58 and the portion 59.

A movable contact member 61 is fixed to an intermediate portion of the rod 60 above the fixed contact 58 and a push button 62 is carried by the upper end of the rod 60 in the path of downward movement of the arm 26. The movable contact 61 is normally held in its raised position out of engagement with the fixed contact by a coiled spring 63 which encircles the rod 60 and the spring has its opposite ends engaging the portion 59 of the switch and the movable contact 61.

The fixed contact 58 is connected to a wire 64 which may form a part of an electric alarm circuit for an alarm, such as, a bell 65. The movable contact 61 is connected to a wire 66 which also form a part of the alarm circuit.

A cover 67 which may be made of brass or other suitable material is of substantially the same length and width as the base 18 so as to fit thereon to protect the switches and the other elements which are mounted on the base. The lower edge portion of the cover is of reduced thickness as indicated at 68 to provide a downwardly facing shoulder 69. The inner face of the reduced portion 68 snugly engages the edge of the base 18 and the shoulder 69 rests upon the upper face of the marginal edge portion of the base. Fastening elements, such as, screws 70 extend through suitable openings in the cover and are received by screw threaded sockets 71 for holding the cover in proper position upon the base 18. The forward wall of the cover has a vertically extending slot 72 to accommodate the arm 26.

In the use of the improved device it may be connected to the electric circuit of the motor 52 which may operate the oil pump of an oil separator. During normal operation of the separator the parts will be in the position illustrated in full lines in Figures 3 and 4 of the drawings. The lever 17 and the cup 31 will be in their raised positions and the contacts 45 and 48 of the switch 41 will be in engagement so that the circuit to the motor 52 is closed. The contacts 58 and 61 of the second switch 54 will be separated so that the alarm circuit is open.

When an oil separator is in operation dirty or contaminated oil is fed into it and purified oil is discharged therefrom. When the separator is operating properly the water which has been separated from the oil is intermittently discharged through the pipe 34. The orifice 33 in the bottom of the cup is of sufficient size to permit the normal flow of the water through the pipe 34 to be discharged through the orifice into the drainage system on land or the bilges on board ship without building up in the cup. For various reasons while the separator is running at times it will fail and oil will be discharged through the overflow pipe and there will be a resultant loss of oil into the drainage system or the bilges. If this failure is not detected the entire tank of oil might be lost and the machinery damaged. The diameter of the orifice 33 of the cup 31 is of such a size, for example, one-fourth of an inch, that the oil which is more viscous than the water will not be able to drain through the orifice at as great a rate as it enters the cup.

Accordingly, the oil will build up in the cup until the weight of the oil in the cup will overcome the resistance of the spring 23 and will lower the cup and swing the forward portion of the lever 17 downwardly on its pivots 15. As the lever 17 moves downwardly the arm 26 will engage and depress the push buttons 49 and 62, causing the contact 48 to move out of engagement with its contact 45 to break the circuit to the motor 52 and thereby stop the operation of the separator. At the same time the contact 61 will be moved to the dotted line position shown in Figure 4 of the drawings in which it engages its contact 58 and closes the alarm circuit to ring the bell 65 to warn the attendant that there has been a machine failure.

When sufficient oil has escaped from the cup

the spring 23 will return the lever 17 to its raised position: the connecting piece 37 of the lever stop 35 limiting the upward movement of the arm 26 and the legs 36 thereof and the opposite sides of the slot 12 of the cover 67 serving as guides to prevent undue horizontal movement of the arm 26. As the arm 26 becomes disengaged from the push buttons 49 and 62 the springs 59 and 63 come into play to raise the rods 47 and 60 so that the contact 48 again engages its contact 45 to close the motor circuit and contact 61 is moved away from its contact 58 to open the alarm circuit. The tension of the spring 23 may be varied by adjusting the member 19 so that the cup may be depressed by any desired amount of oil gathered therein.

The cup, the lever and its supporting structure and the lever stop may be made of sheet brass one-sixteenth inch thick or of any other suitable material having the desired thickness.

It is obvious that various changes and modifications may be made in the details of construction and design of the above specifically described embodiment of this invention without departing from the spirit thereof, such changes and modifications being restricted only by the scope of the following claims:

What I claim is:

1. An automatic cut-out switch for the electric circuit of an oil separator having an outlet through which water discharges during normal operation of the separator and through which oil discharges during a failure of the separator comprising a pivotally mounted lever, a cup carried by said lever and having an orifice therein, a switch for normally closing said circuit and having an operating member disposed in the path of movement of said lever, and resilient means for holding said lever out of engagement with said operating member, said cup adapted to receive discharging water from the outlet of the separator during the normal operation of the separator and to receive discharging oil from the outlet of the separator during a failure of the separator, said orifice being of such a size that the water will escape from the cup at the same rate as it enters the cup and that the oil will not escape from the cup at as great a rate as it enters the cup so that the oil will accumulate in the cup until its weight overcomes the force of the resilient means for holding the lever out of engagement with said operating member, thereby causing the lever to move downwardly into engagement with said operating member to open the separator circuit.

2. An automatic cut-out switch as claimed in claim 1 characterized by the fact that an alarm is provided, that an electric circuit is provided for said alarm and includes a normally open switch having an operating member disposed in the path of movement of said lever, whereby the downward movement of the lever causes the lever to engage the operating member of said alarm switch to close the alarm circuit.

3. An automatic cut-out switch for the electric circuit of an oil separator having an outlet through which water discharges during normal operation of the separator and through which oil discharges during a failure of the separator comprising a base, a lever support on said base, a lever pivotally mounted on said support, a cup on said lever and having an orifice therein, a switch on said base for normally closing said circuit and having an operating member disposed in the path of movement of said lever, an alarm circuit

comprising an alarm, a normally open switch for said alarm circuit and mounted on said base and comprising an operating member disposed in the path of movement of said lever, and resilient means connected to said support and said lever for holding said lever out of engagement with said operating members, said cup adapted to be positioned beneath said outlet to receive discharging water from the separator during the normal operation of the separator and to receive discharging oil from the separator during a failure of the separator, said orifice being of such a size that the water will escape from the cup at the same rate as it enters the cup and that the oil will not escape from the cup at as great a rate as it enters the cup so that the oil will accumulate in the cup until its weight overcomes the force of the resilient means for holding the lever out of engagement with said operating members, thereby causing the lever to move downwardly into engagement with said operating members to open the separator circuit and to close the alarm circuit.

4. An automatic cut-out switch as claimed in claim 3 characterized by the fact that adjusting means are provided for varying the tension of said resilient means.

5. An automatic cut-out switch as claimed in claim 3 characterized by the fact that said resilient means urges said lever upwardly out of engagement with said operating members, and that a lever stop is mounted on said base for arresting the upward movement of the lever under the influence of said resilient means.

6. An automatic cut-out switch as claimed in claim 3 characterized by the fact that one end portion of said lever extends beyond said base, that the cup is secured to the extended portion of the lever, and that a cover is provided for attachment to said base for enclosing the support, the lever, and the switches, said cover having a vertically extending slot therein for receiving therethrough the extended portion of the lever.

7. An automatic cut-out switch for the electric circuit of an oil separator having an outlet through which water discharges during normal operation of the separator and through which oil discharges during a failure of the separator comprising movable means, an electric switch for normally closing the separator circuit and having an operating member disposed in the path of movement of said movable means, and means for holding said movable means against movement, said movable means comprising a cup having an orifice therein and adapted to be disposed in the path of the water and oil being discharged from the outlet of the separator during operation of the separator, said orifice being of such a size that the water will escape from the cup at the same rate as it enters the cup so that the movable means will not be affected and that the oil will not escape from the cup at as great a rate as it enters the cup so that the oil will accumulate in the cup until its weight overcomes the force of the means holding the movable means against movement, thereby causing the movable means to engage the operating member and open the separator circuit.

8. An automatic cut-out switch for the electric circuit of a separator for separating two liquids of different viscosities and having an outlet through which the liquid of less viscosity discharges during normal operation of the separator and through which the liquid of greater viscosity discharges during a failure of the separator

comprising movable means, an electric switch for normally closing the separator circuit and having an operating member disposed in the path of movement of said movable means, and resilient means for holding said movable means against movement, an alarm, an electric circuit for said alarm including a normally open switch having an operating member disposed in the path of movement of said movable means, said movable means comprising a cup having an orifice therein and adapted to be disposed in the path of the liquids being discharged from the outlet of the separator during operation of the separator, said orifice being of such a size that the liquid of less viscosity will escape from the cup at the same rate as it enters the cup so that the movable means will not be affected and that the liquid of greater viscosity will not escape from the cup at as great a rate as it enters the cup so that the liquid of greater viscosity will accumulate in the cup until its weight overcomes the force of the means holding the movable means against movement, thereby causing the movable means to engage the operating member and open the separator circuit and to close the alarm circuit.

9. An automatic cut-out switch for the electric circuit of a separator for separating two liquids of different viscosities and having an outlet through which the less viscous liquid discharges during normal operation of the separator and through which the more viscous liquid discharges

10
1520
25
